UNITED STATES PATENT OFFICE.

WILLIAM C. HEDGCOCK, OF CHICAGO, ILLINOIS, ASSIGNOR TO AMERICAN STEEL FOUNDRIES, OF CHICAGO, ILLINOIS, A CORPORATION OF NEW JERSEY.

REVERSIBLE FULCRUM.

Application filed September 12, 1921. Serial No. 499,836.

To all whom it may concern:

Be it known that I, WILLIAM C. HEDGCOCK, a citizen of the United States, residing at Chicago, in the county of Cook and State 5 of Illinois, have invented certain new and useful Improvements in a Reversible Fulcrum, of which the following is a specification.

This invention relates to brake beams and 10 more particularly to a reversible fulcrum combination.

One object of the invention is to provide a simple and efficient reversible fulcrum for brake beams which is adapted to meet the 15 various requirements of a fulcrum which may be used right-hand and left-hand and at the same time prevent the existence of lost motion and properly perform its function as a strut of the brake beam truss.

Another object is to provide a reversible 20 fulcrum arrangement in which while the fulcrum body is clamped to prevent lost motion longitudinally of the fulcrum body, the latter may be rotated from one position to 25 another relatively freely.

These and other objects are accomplished by means of the arrangement disclosed by the accompanying sheet of drawings, in which—

Figure 1 is a fragmentary top plan view 30 of a brake beam embodying my invention, the compression member being shown in section for the sake of clearness;

Figure 2 is a side elevation of the fulcrum body and associated parts, with the 35 brake beam tension and compression members shown in section; and

Figure 3 is a sectional view taken in the plane of line 3—3 of Figure 2.

The various novel features of the invention 40 will be apparent from the following description and drawings and will be particularly pointed out in the appended claims.

Referring to the figures of the drawings, 45 it will be noted that I have disclosed my invention in connection with a truss type of brake beam including a compression member 10, a tension member 11, and a fulcrum 12 extending between the tension and compression members. The main body portion 13 of the fulcrum includes two spaced arms 14 between which a brake lever, not shown, may be pivotally mounted. The fulcrum body here illustrated is an integrally formed 50 and closed rectangular body the rear end

wall of which is provided with an opening 15, the purpose of which will appear later. A clamping member 16 is secured to the web 17 of the compression member by any suitable means, such as rivets 18. The clamping member has its intermediate portion 19 offset with respect to the web 17 of the compression member and the extent of the offset is less than the width of the head 20 of a rivet-like member, the intermediate portion 21 of which extends loosely through an opening 22 in the clamping member 16. Extending from the intermediate portion 21 of the headed member 20 is a reduced portion 23 which extends through the opening 15 in the fulcrum body 13 and is riveted to said fulcrum body, a rivet head 24 being formed. It will be noted that the intermediate portion 21 of the rivet-like member extends loosely through the opening 22 in the clamping member 16 to increase the freedom of movement of the fulcrum body 13 as it is oscillated from one position to another. This reversible movement, however, is resisted somewhat in view of the fact that the head 20 is clamped between the web 17 of the compression member and the clamping member 16 which prevents any lost motion longitudinally of the fulcrum body, thereby 70 permitting the latter to act as a perfect strut in the brake beam truss. It will be noted also that one end of the intermediate portion 21 of the rivet-like member engages the rear end wall of the fulcrum body and holds it spaced from the intermediate portion 19 of the clamping member 16.

The rear portion of the fulcrum body 13 is provided with angular faces 29 which are adapted to engage the upper and lower flanges 25 and 26 of the compression member for limiting the reversible movements of the fulcrum body. This connection between the fulcrum body and the compression member provides a practical arrangement which is adapted to meet the requirements for successful commercial use.

Pivots connected to the front end of the fulcrum body by a rivet 27 is a tension rod saddle 28 which receives the tension rod 11.

It is my intention to cover all modifications of the invention falling within the spirit and scope of the following claims.

I claim:

1. In a brake beam, the combination of a 110

- compression member, a reversible fulcrum body having an opening therein, a clamping member having an opening and being secured to said compression member, and a headed member having a portion extending through the opening in said fulcrum body and riveted thereto and having another portion extending loosely through the opening in said clamping member to facilitate easy rotation of the fulcrum body, the headed portion of said headed member being clamped between said clamping member and compression member to prevent lost motion longitudinally of the fulcrum.
15. 2. In a brake beam, the combination of a compression member, a reversible fulcrum body, a clamping member having an opening and being secured to said compression member, and a member headed at one end for securing it to said fulcrum body, said headed member having another portion extending loosely through the opening in said clamping member to facilitate easy rotation of the fulcrum body, said headed member having another head which is clamped between said clamping member and compression member to prevent lost motion longitudinally of the fulcrum body.
20. 3. In a brake beam, the combination of a compression member, a reversible fulcrum

body, a clamping member having an opening and being secured to said compression member, and a member headed at both ends, one headed end being secured to said fulcrum body, an intermediate portion extending loosely through the opening in said clamping member to facilitate easy rotation of the fulcrum body and engaging said fulcrum body to space it from the clamping member, the other headed end being clamped between said clamping member and compression member to prevent lost motion longitudinally of the fulcrum body.

4. In a brake beam, the combination of tension and compression members, a fulcrum body, a clamping member secured to one of said members, and a rivet-like member headed at both ends whereby one end is secured to said fulcrum body and the other clamped between said clamping member and one of said other members for preventing lost motion longitudinally of the fulcrum, said rivet-like member also having a portion extending loosely through an opening in said clamping member to facilitate rotation of the fulcrum body.

Signed at Chicago, Illinois, this 3rd day of September, 1921.

WILLIAM C. HEDGCOCK.
